United States Patent Office.

ANDREW HUNTER, OF SAN FRANCISCO, CALIFORNIA.

Letters Patent No. 80,629, dated August 4, 1868; antedated July 25, 1868.

IMPROVED MACHINE FOR SEPARATING AND CONCENTRATING SULPHURETS.

The Schedule referred to in these Letters Patent and making part of the same.

TO ALL WHOM IT MAY CONCERN:

Be it known that I, ANDREW HUNTER, of the city and county of San Francisco, State of California, have invented a new and useful Improvement in Machines (heretofore invented by me) for Separating and Concentrating Sulphurets from ores, sands, or tailings, whether of gold, silver, or other metals, and for saving amalgam, (a patent for which machine was granted me on the 23d day of May, 1865;) and I do hereby declare that the following is a full and exact description of same, reference being had to the accompanying drawings, and to the letters of reference marked thereon.

Figure 1 is an end view of the machine.

Figures 2 and 3 are side views.

Figure 4 is a plan.

A A is a stout framework.

B is a table or trough of wood, having a downward inclination from rear to front, for a portion of its length, as shown by line *a b*, and is level, or nearly so, from *b* to *d*.

D D are adjustable hangers, of steel or other proper material, by which the rear end of table or trough B is suspended at any required height.

S is a shaft, with wheels or rollers R, or other suitable device, upon which the front end of the table or trough B rests and moves.

K is a shaft, provided with crank or eccentric, revolved by any known means giving a quick oscillatory or vibratory motion.

Z is an eccentric-strap, constructed so that the space shall be filled by the eccentric, when in position at top of the strap, arresting for a moment the vibratory motion of the table or trough B. When the eccentric is at the lower part of the strap, there is room for play, so that the table or trough B may have the full vibratory motion.

X is a spring, against which the table or trough B strikes.

E is a small trough or hopper (with holes in the bottom) to receive the pulp and distribute it equally upon the table or trough B, and has a rocking motion given to it by rod I, driven by crank on shaft S.

G is a smaller trough, supplied with water from pipe H, which drips slowly through small holes on to the table or trough B.

T is an inclined sieve, having a vibratory motion by means of rod or standard U and rod V, driven by a crank on shaft K.

W is a scraper, of rubber or other suitable material, revolving on a shaft, for the purpose of removing the sands from the table or trough B.

Operation.

The machine being set in motion, the pulp or tailings is run into trough E, and is distributed through the holes in the same. The heavier particles, say sulphurets or metal, are precipitated upon the table or trough B, and being below the current, and free from its influence, are forced over the upper end of the table or trough, by reason of this quick, oscillatory motion, and the concussion produced by the striking of the trough or table B against spring X, or its equivalent. The degree of concussion is regulated by placing the spring X nearer to or farther from the table or trough, by means of set-screws or other suitable device. The lighter or earthy or sandy particles are held in suspension by the water, and pass down over the lower end of the table or trough B, assisted by scraper W, on to the sieve or screen T. The floured or fine particles of metal pass through into a proper receptacle, the sands and other coarse matter passing over the lower end.

Having thus described my machine and its operation, what I claim as my invention, and desire to secure by Letters Patent, is—

1. The formation of the trough or table B, with or without metallic lining, and alternately inclining and level, as shown by lines *a b d*, substantially as described, and for the uses and purposes as set forth.

2. The combination, with the table or trough B and its adjustable hangers, of the cam-shaft and spring X, under the arrangement described, whereby both the oscillatory motion and percussion of the said table are effected, for the purpose of separating the sulphurets and metals from the lighter particles, as set forth.
3. The eccentric-strap Z, in combination with the trough B and cam, or equivalent means, for imparting an oscillatory movement to said trough, substantially as and for the purposes set forth.
4. The combination, with the table B and mechanism for imparting to the same an oscillatory movement, of the rocking-trough E, arranged for operation substantially as and for the purposes set forth.
5. The combination, with the oscillatory table or trough B, of the rotary scraper W, made of India rubber or other suitable material, substantially as set forth, and for the purposes specified.
6. The combination, with the table or trough B, of the inclined screen T, and mechanism for imparting to the same a vibratory motion, under the arrangement and for operation as herein set forth.
7. The combination, with the oscillating trough and hanger, by which the rear end of the trough is held, of the wheels or rollers R, for supporting the front end of said trough, substantially as herein shown and described.
8. The combination of the table or trough B with eccentric-troughs E and G, hangers D D, spring X, wheels or rollers R, scraper W, and sieve T, substantially as described, and for the uses and purposes as hereinbefore set forth.

In testimony whereof, I have signed my name to this specification before two subscribing witnesses.

ANDREW HUNTER.
